213,172

BOTTLE

Frederick W. Muller, Shawnee Mission, Kans., assignor to Cook Chemical Company, Kansas City, Mo., a corporation of Missouri

Filed Nov. 20, 1967, Ser. No. 9,478

Term of patent 14 years

U.S. Cl. D9—127
Int. Cl. D9—01

FIGURE 1 is a side elevational view of a bottle showing my new design;

FIG. 2 is a plan view;

FIG. 3 is a fragmentary front elevational view; and
FIG. 4 is a fragmentary rear elevational view.

The dominant features of the design are shown in full lines.

I claim:

The ornamental design for a bottle, as shown and described.

References Cited

UNITED STATES PATENTS

D. 199,591 11/1964 Speicher _____ D9—39
D. 201,258 6/1965 Fillmore _____ D9—18

ROBERT C. SPANGLER, Primary Examiner.